UNITED STATES PATENT OFFICE.

ALBERT J. CROLL, OF ROCHESTER, NEW YORK, ASSIGNOR TO NORTH EAST ELECTRIC COMPANY, OF ROCHESTER, NEW YORK, A CORPORATION OF NEW YORK.

FIELD-MAGNET.

1,314,128.

Specification of Letters Patent.

Patented Aug. 26, 1919.

Application filed July 26, 1918. Serial No. 246,930.

To all whom it may concern:

Be it known that I, ALBERT J. CROLL, a citizen of the United States, residing at Rochester, in the county of Monroe and 5 State of New York, have invented certain new and useful Improvements in Field-Magnets; and I do hereby declare the following to be a full, clear, and exact description of the invention such as will enable 10 others skilled in the art to which it appertains to make and use the same.

This invention relates to a field-magnet for use in electric motors or generators, or other apparatus.

15 In dynamo-electric machines of the "iron-clad" type, in which the field-poles are in the form of inward projections from a ring or shell of iron, it is common to use windings, upon the polar projections, comprising 20 form-wound coils which are placed, already wound, on the projections. To combine magnetic efficiency with economy of material, the polar projections should have comparatively slender necks and wide faces, 25 but this form introduces difficulty in applying the coils to the projections, unless the projections are made separable, in whole or in part, from the ring or shell of the field-magnet.

30 The object of the present invention is to produce a field-magnet, of the type in question, in which the polar projections are integral with the body-members by which they are magnetically connected, but in 35 which the coils may be easily applied to and removed from the necks of the polar projections.

To the foregoing end the invention resides in a field-magnet made up of several 40 members, equal in number to the polar projections. Each member consists of one or more sections, according as it is of solid or laminated construction, and these sections have a form characteristic of the invention. 45 Each section comprises a neck-portion, adapted to receive a coil, and horns projecting from the inner end of the neck so as to provide a wide polar face. From one side only of the neck, at its outer end, projects a body-member which is formed to extend into engagement with the neck-portion of the next adjacent polar projection, thus connecting the projections magnetically. 50 The body-portion is of a width no greater than that of the neck, and is preferably

united to the latter by a smooth curve, so that the coil may be passed over the body-portion lengthwise and swung into position upon the neck.

Other features of the invention will be pointed out in connection with the following description of the illustrated embodiment thereof.

In the accompanying drawings Figure 1 is a side-elevation of a field-magnet embodying the present invention, with one of the coils shown in section. Fig. 2 is a side-elevation of one member of the magnet, showing the manner in which the coil is applied. Fig. 3 is a side-elevation showing the manner in which the parts are assembled in constructing the magnet in a modified form, and Figs. 4 and 5 are detail-views in side-elevation and plan, respectively, of such modified form. Fig. 6 is a side-elevation, partly in vertical section, of an embodiment of the invention in a four-pole field-magnet.

In Figs. 1 and 2 the invention is shown as embodied in a field-magnet of laminated construction, with two poles. The magnet 80 comprises two core-members, each made up of any convenient number of similar laminæ or sections. Each section comprises a neck 10, from which horns 11 extend in opposite directions, thus producing a polar projection of conventional form.

From one side of the neck 10 a body-portion 12 extends, being united with the neck by smooth curves. Each body-portion has an extremity 13 which is concave so as to fit 90 closely against the convex surface 14 of the neck of an adjacent polar projection. Consequently, the body-portions constitute magnetic connections or yokes between the projections or poles. The several laminæ of 95 each member are shown as secured together by rivets 16, while the two members so constituted may be held in the relative position shown in Fig. 1 by any convenient means.

The construction just described has two 100 important and correlative advantages; the sections may be inexpensively formed by punchings of sheet-metal, and coils already formed and taped may be easily put in place on the necks of the polar projections. The 105 manner in which the coils are so placed is clearly illustrated in Fig. 2.

In the construction shown in Fig. 1 the members must be held in co-operative relation by extraneous means. To gain greater 110

- mechanical strength, and to reduce the magnetic reluctance of the joints between the members, it may be desirable to arrange the laminae of adjacent members in overlapping relation. This may be done, without any alteration of the shape of the sections, as shown in Figs. 3, 4 and 5. In this case the alternate sections forming each polar projection are arranged with their body-portions extending in opposite direction, so that they overlap and alternate with the body-portions of the sections forming the opposite polar projection. The rivets 16 then act to secure all of the sections rigidly together, in a unitary core-structure.
- In using the sections as just described it is necessary to apply the coils before the sections are riveted together. This is done by introducing the body-portions of the sections into each coil two at a time and from opposite sides, as shown in Fig. 3. After the sections forming each polar projection have thus been brought to their proper relative position, with the coil encircling their neck-portions, the assembly so formed may be properly correlated with another similar assembly, by interposing the respective body-portions, and the rivets may then be introduced.
- By changing the extent of the body-portions the construction characteristic of the present invention may be applied to the formation of multipolar as well as bi-polar magnets. Fig. 6 shows a 4-pole magnet so

formed. In this case the members are shown as each comprising only a single solid section, though the laminated structures of Figs. 1 and 4 may be used with equal facility.

As a convenient means for securing the members or sections together, when the construction of Fig. 4 is not used, the members may be closely embraced in and supported by an inclosing shell or ring 17, of magnetic or non-magnetic material.

While the illustrated sections are all shaped to produce a magnet of a generally circular form, this is not an essential feature of the invention, and the invention is not, in general, limited to the details of construction of the illustrated embodiments thereof.

The invention claimed is:

1. A field-magnet consisting of a plurality of sections, each section comprising a neck adapted to receive a coil; horns projecting from the inner end of the neck; an elongated body-portion extending, from one side only of the neck, into engagement with the neck of another section; and coils on the necks.
2. A field-magnet, as in claim 1, in which said sections are in the form of laminae superposed in the neck-portion and with their body-portions extending alternately in opposite directions from the neck-portion, so as to interlock with the body-portions of the sections constituting the next adjacent pole or poles.

ALBERT J. CROLL.
